UNITED STATES PATENT OFFICE

FRED ASHWORTH, OF BEVERLY, MASSACHUSETTS, ASSIGNOR TO UNITED SHOE MACHINERY CORPORATION, OF PATERSON, NEW JERSEY, A CORPORATION OF NEW JERSEY

SEWING MACHINE

Application filed April 5, 1924. Serial No. 704,414.

The invention relates to hook needle sewing machines such as are used in the manufacture of boots and shoes.

The invention may be utilized with particular advantage in machines designed for doing stab shank work although not confined in its application to such machines. In doing this class of work the outsole is secured to the shoe through the shank portions by lock stitch seams passing through the outsole, upper and insole or in some cases through the outsole and upper only. Machines for doing this work are therefore provided with a work supporting horn adapted to enter the shoe and support it by engagement with the insole or interior of the upper. Certain features of the invention provide stitch forming mechanism which is well adapted for rapid and efficient operation in this type of machine, other features provide simple, efficient and durable work feeding devices for this type of machine, while still other features enable the operator to conveniently and readily remove the work from the horn after the seam is completed.

The invention is illustrated in the accompanying drawings as embodied in a lock stitch sewing machine adapted for stab shank work. Figure 1 is a right hand side elevation of the machine; Fig. 2 a left hand side elevation; Fig. 3 a front elevation; Fig. 4 a horizontal sectional view on line 4—4 of Fig. 3; Fig. 5 a diagrammatic view showing the bottom of the insole and the location of the seam sewed along the shank portion; Fig. 6 a vertical sectional view on line 6—6, Fig. 2; Fig. 7 a horizontal sectional view on line 7—7, Fig. 2; Fig. 8 a vertical sectional view on line 8—8, Fig. 3; Fig. 9 a detail side elevation showing the mechanism for unlocking and lifting the presser foot and throwing off the tension; and Figs. 10 to 18 inclusive are diagrammatic views showing the mode of operation of the stitch forming and work feeding devices.

The machine shown is provided with a curved hook needle 2, needle guide 4, shuttle 6, thread spreader 8, presser foot 10, thread lock 12, pull-off 14 and take-up 16, all of which have the same construction as corre-

sponding parts in the machine shown and described in Patent No. 473,870 dated April 26, 1892, and all of which are operated from the cam shaft 18 through connections fully shown and described in said patent.

To adapt the machine for stab shank work, it is provided with a work supporting horn 20 adapted to enter an unlasted shoe and support it by engagement with the insole or by engagement with the upper just outside the insole. The horn is secured to the upper end of a base in the form of a post 22 and is provided with a throat or opening 24 for the passage of the needle.

The needle is threaded by a forked looper 26 mounted within the horn to move laterally across the line of feed and place the thread in the needle hook with a minimum movement beyond the needle when at the end of its work piercing stroke. This form of looper thus enables the seam to be conveniently located by the operator close to (or even beyond) the edge of the insole, as indicated in Figs. 10 to 18, while guiding the work by engagement of the edge of the outsole with a guide 28 on the rear of the presser foot or by engagement of the channel with the outer edge of the presser foot. A thread measuring finger 30 is also arranged within the horn to move laterally in the line of feed in drawing the thread and thus position it across the fork of the looper. To facilitate the action of the thread finger in drawing its thread, the looper is given a vertical or longitudinal movement in the direction of the lead of the thread so that the thread finger draws the thread obliquely instead of directly across the end of the looper. A vertically and laterally reciprocating awl 32 is also arranged within the horn and operates to feed the work.

The awl is secured to the upper end of an awl bar 34 mounted in a vertical guideway 36 at the end of an arm 38 which projects from a feed slide 40. The feed slide is mounted in a fixed guideway 42 and is operated from a cam on the cam shaft through a cam lever 44 and an adjustable connecting link 46 similar to the feed cam lever and link of the above patent. The link may be adjusted by a handle

48 extending between pins 50 inserted in holes in the plate 52 on the feed slide and determines the position of the link and the length of the stitch. The forward end of the link 5 is connected to an arm 54 rising from the arm 56 of the feed slide. The awl bar is moved vertically through a rock shaft 58 arranged back of the post 22 and provided with a gear segment 60 engaging rack teeth on 10 the bar. The shaft is also connected to operate the looper and thread finger and is itself actuated from the cam shaft through a cam lever 62 and a link 64 which connects the lever with an arm 66 on the rock shaft.

15 The looper comprises a vertically arranged finger, the upper end of which is forked to embrace the needle, one arm of the fork being perforated for the passage of the thread and the other being notched to engage the 20 thread drawn laterally by the thread finger. The lower end of the looper is secured in the upper end of a vertical looper arm 68, the lower end of which is pivoted to a vertically movable lever 70. The front end of the lever is pivoted at 72 to the base 22 and the rear end of the lever is connected by a link 74 with the arm 66 of the rock shaft 58. Through this connection with the shaft 58, the looper is moved vertically toward the work as the awl 25 withdraws and the needle advances through the work and is moved vertically away from the work as the awl advances and the needle is retracted. The looper is given its lateral movement to place the thread in the hook of 30 the needle by a cam slot 76 formed in the looper arm and engaged by a fixed pin 78 projecting from a bracket 80 secured to the post 22. The upper portion of the slot 76 is vertical while the lower end is laterally inclined so that the looper will move vertically 35 into position in front of the needle and then laterally to carry the thread against the needle and into position to enter its hook, as indicated in Figs. 16 and 18.

40 The thread finger 30 is carried on the upper end of a vertical lever 82 which is pivoted at 84 in a bracket 86 secured to the side of the awl bar guideway 36 and the lower end of which carries a roll engaging a cam 45 groove 88 formed in a cam segment 90 which is secured to the rock shaft 58. Lateral movement in the line of feed is thus imparted to the thread finger by the reciprocation of the feed slide and also by the inclined part of the 50 cam groove 88.

55 The mode of operation of the devices operating within the horn is indicated diagrammatically in Figs. 10 to 18. In Figs. 10 and 11 the awl, looper and thread finger are shown 60 in their relative positions after the completed stitch has been set and the awl has moved back preparatory to the next feed and has partially advanced toward the work, the looper having been partially retracted away 65 from the work and the thread finger having

been partially retracted by the return movement of the feed slide and awl. The awl then advances through the work, the looper completes its movement away from the work and the backward movement of the thread finger 70 is completed by the action of the inclined portion of the cam groove 88 on the thread finger lever, the position of the parts at this stage being shown in Figs. 12 and 13. The awl is then moved to feed the work and during this movement the thread finger is moved toward the thread which leads from the looper to the previous stitch, the position of the parts at this stage being shown in Figs. 75 14 and 15. The awl is then retracted and the 80 needle advanced through the work. During the first part of the downward movement of the awl and the first part of the upward movement of the looper, the inclined part of the cam groove 88 swings the thread finger laterally into the position indicated in Fig. 17, the thread drawing obliquely and freely through the hole in the looper as the looper is advancing from its lowest position indicated in Fig. 15 toward its highest position 85 indicated in Fig. 17. After the thread finger has drawn its thread, the upward movement of the looper and downward movement of the awl continues, bringing the parts into the position indicated in Figure 17. As the 90 looper moves upward, the thread leading from the hole in the looper to the thread finger lays across the fork at the end of the looper and during the final upward movement of the looper it is moved laterally across 95 the line of feed carrying the thread against the needle and into position to be engaged by its hook, as indicated in Figs. 16 and 18. The needle then retracts drawing the loop of 100 thread through the work and into position to be taken by the thread spreader 8 and presented to the shuttle, and the awl moves back 105 preparatory to the next feed.

110 As shown in full lines in Fig. 2, the needle thread leads from the usual wax pot, not shown, about the tension wheel 92, over the roll of the pull-off 14, about the roll 94 of the thread lock, over guide roll 96, take-up roll 16 and guide roll 98 to an auxiliary spring 115 operated take-up 100, from which it leads to the looper. In doing certain classes of work, it is desirable to set the stitch by the take-up directly against the tension instead of against a thread lock, thus avoiding the use of a 120 thread pull-off controlled from the presser foot. Such a construction is indicated in dotted lines in Fig. 2 which show the thread leading from the tension wheel directly to the guide roll 96. This manner of setting the 125 stitch avoids the formation of one or more comparatively loose stitches at the beginning of the seam, such as frequently occur when utilizing a thread lock and a pull-off which pulls off a length of thread measured by the 130 position of the presser foot. The provision

of means, such as a clip indicated at 102, for holding the free end of the needle thread at the beginning of the seam also contributes to the proper formation of the initial stitches in 5 a machine of this character since thereby the auxiliary take-up will be uniformly held at the limit of its movement against the tension of its spring at the beginning of the seam and the presence of any slackness in the thread 10 between the work and the tension (or thread lock) during the initial operation of the take-up thus uniformly avoided.

To facilitate the removal of the work at the completion of the seam, treadle operated 15 means is provided through which the operator may unlock and lift the presser foot and throw off the tension while having both hands free for manipulating and moving the shoe. An embodiment of such means 20 is shown in Fig. 9. As herein shown, a lever 104 is mounted on the pivotal support 106 for the presser foot levers and is provided at its lower end with fingers 108 arranged to engage pins 110 on the presser 25 foot locking pawls 112 and disengage these pawls from the ratchets 114 on the presser foot locking levers. The upper end of the lever 104 is pivoted to the lower end of a lever 116 which is in turn pivotally connected 30 to the forward end of a spring pressed bar 118. The upper end of the lever 116 is connected by a cord 120 with a treadle 122 arranged at the base of the machine. The pivot pin 124 which connects the lever 116 35 with the bar 118 projects laterally into position to engage an arm 126 secured to the presser foot lever. When the treadle is depressed, the lever 116 is rocked about the pivot 124, thus rocking the lever 104 to dis- 40 engage the presser foot locking pawls and then a projection 128 on the lever 104 engages a fixed stop 130 which prevents further movement of the lever 104. The lever 116 then rocks about its pivotal connection with 45 the lever 104 so that the pin 124 acts on the arm 126 to raise the presser foot. The treadle 122 is also connected by a rod 132 with the horizontal arm of a bell crank lever 134 which operates to disengage the spring 50 pressed friction disk 127 from the hub of the tension wheel 92 and thus throw off the tension. The lower end of the tension releasing rod 132 is slotted at 136 to provide a 55 limited lost movement between the treadle and rod so that the first downward movement of the treadle releases and raises the presser foot after which continued movement throws off the tension.

60 What is claimed is:

1. A sewing machine having, in combination, a hook needle, a forked looper longitudinally movable, and also movable laterally across the line of feed, and a thread finger movable with relation to the looper

and engaging the thread between the looper and the work.

2. A sewing machine having, in combination, a hook needle, a forked looper, a thread finger arranged to engage the thread between 70 the looper and the work and movable laterally to draw thread through the looper and across its fork, and mechanism for moving the looper toward and away from the work and laterally across the line of feed. 75

3. A sewing machine having, in combination, a hook needle, a thread finger arranged to engage the thread between the looper and the work, a forked looper movable toward and away from the work, means for moving the thread finger laterally to draw thread through the looper when retracted, and means for advancing the looper and moving it laterally across the line of feed after the thread finger has acted. 80

4. A sewing machine having, in combination, a needle on one side of the work, an awl, thread finger and forked looper on the other side of the work, and mechanism for advancing and retracting the awl and for moving the looper away from the work as the awl advances and for moving it toward the work and laterally across the line of feed as the awl retracts. 85

5. A sewing machine having, in combination, a hook needle on one side of the work, an awl, forked looper and thread finger on the other side of the work, mechanism for moving the awl and looper alternately toward and from the work and for moving the thread finger laterally in the line of feed to draw thread through the looper while retracted. 90

6. A sewing machine having, in combination, a hook needle, a work supporting horn and a forked looper and thread finger within the horn, the thread finger being movable with relation to the looper and arranged to engage the thread between the looper and the work. 95

7. A sewing machine having, in combination, a hook needle, a work supporting horn, and a forked looper, thread finger and work feeding awl within the horn, the thread finger being movable with relation to the looper and arranged to engage the thread between the looper and the work. 100

8. A sewing machine having, in combination, a hook needle, a work supporting horn, means within the horn for threading the needle, a feed slide, and an awl mounted on the slide within the horn. 105

9. A sewing machine having, in combination, a hook needle, a work supporting horn, means within the horn for threading the needle, a feed slide having an arm extending into the base of the horn, and an awl carrying bar mounted to reciprocate in the arm. 110

10. A sewing machine having, in combination, a hook needle, a work supporting horn, 115

- a feed slide, an awl mounted on the slide within the horn, a thread finger mounted on the slide within the horn, and a looper within the horn.
- 5 11. A sewing machine having, in combination, a hook needle, a work supporting horn, a feed slide, an awl bar and a thread finger mounted on the slide within the horn, a rock shaft connected to reciprocate the bar and to 10 oscillate the thread finger, and a looper within the horn.
12. A sewing machine having, in combination, a hook needle, a work supporting horn, an awl, thread finger and looper within the 15 horn, and a rock shaft connected to reciprocate the awl, actuate the looper and oscillate the thread finger.
13. A sewing machine having, in combination, a hook needle, a work supporting horn, 20 a feed slide, an awl bar mounted to reciprocate in the slide and operating within the horn, a thread finger within the horn, a looper within the horn, a rock shaft provided with a gear segment engaging rack teeth on the bar, 25 a cam for oscillating the thread finger, and an arm connected to oscillate the looper.
14. A sewing machine having, in combination, a hook needle reciprocating through the work in a substantially vertical direction, a 30 thread finger movable with relation to the looper and engaging the thread between the looper and the work, a vertically reciprocating looper arm, a forked looper at the end of the arm, and means for moving the looper end 35 of the arm laterally across the line of feed to thread the needle.
15. A sewing machine having, in combination, a hook needle reciprocating through the work in a substantially vertical direction, a 40 vertical looper arm provided with a guiding slot having a lateral off-set at one end, a forked looper at the end of the arm, a vertical oscillating lever connected to the other end of the arm, and a pin engaging the slot in 45 the looper arm.
16. A sewing machine having, in combination, a hook needle, a shuttle, a presser foot, a work supporting horn, and an awl, forked looper and thread arm operating within the 50 horn, the thread finger being movable with relation to the looper and arranged to engage the thread between the looper and the work.
17. A sewing machine having, in combination, a hook needle, a shuttle, a work supporting 55 horn, a looper and thread finger within the horn, a take-up, an auxiliary spring take-up, and a clip for holding the end of the needle thread against the pull of the auxiliary take-up during the sewing of the initial 60 stitches.
18. A sewing machine having, in combination, a hook needle, a shuttle, a work supporting horn, a looper and thread finger within the horn, a tension for the needle thread a 65 take-up arranged to set the stitch directly

against the tension, an auxiliary spring take-up, and a clip for holding the end of the needle thread against the pull of the auxiliary take-up during the sewing of the initial 70 stitches.

19. A sewing machine having, in combination, a hook needle, a shuttle, a work supporting horn, a presser-foot, a looper and thread finger within the horn, a tension for the needle thread, a take-up, mechanism for actuating and locking the presser-foot, a treadle, and connections between the treadle and presser-foot actuating and locking mechanism and tension actuated directly by the movement of the treadle for unlocking and 80 lifting the presser-foot and releasing the tension.

20. A sewing machine having, in combination, stitch forming mechanism including a hook needle, a shuttle, a thread finger, a looper, a tension for the needle thread, a work support, a presser-foot, mechanism for actuating and locking the presser-foot, a treadle, and connections between the treadle and the presser-foot actuating and locking mechanism and tension actuated directly by the movement of the treadle for unlocking and 90 lifting the presser-foot and releasing the tension.

In testimony whereof I have signed my 95 name to this specification.

FRED ASHWORTH.
